United States Patent Office.

JOHN S. DUTTON, OF JAFFREY, NEW HAMPSHIRE.

Letters Patent No. 82,697, dated October 6, 1868.

IMPROVEMENT IN SCREW-PLATES.

The Schedule referred to in these Letters Patent and making part of the same.

TO ALL WHOM IT MAY CONCERN:

Be it known that I, JOHN S. DUTTON, of Jaffrey, in the county of Cheshire, and State of New Hampshire, have invented a new and useful Improvement in Screw-Plates; and I do hereby declare that the following is a full, clear, and exact description thereof, which will enable others skilled in the art to make and use the same, reference being had to the accompanying drawings, forming part of this specification.

The drawing represents a screw-plate provided with my invention.

The object of this invention is to provide a convenient means of cutting any number of screws of equal size with the ordinary screw-plate.

This I accomplish by means of a gauge-collar, which is movable on the screw, which closes the dies, and which is further provided with a set-screw to affix it at any point on the said screw, and thus limit the movement of the screw in closing the dies. Suitable marks or indices are engraved on the collar and on the proximate reduced end of the screw-plate, against which the collar is in contact when the closing of the dies is stopped.

In the accompanying drawing—

A is an ordinary screw-plate, with dies B B of the usual form.

C is the screw for closing such dies upon the work embraced by them, and

D is the handle of the said screw, which serves with opposite similar handle, forming part of the plate, to operate the tool.

The collar *a* slips freely on the screw *C*, and may be held tightly at any point by means of the set-screw *g* or other equivalent device.

The collar is marked with an index-mark, *e*, as is also the reduced circular end *b* of the plate *A*, against which the collar fits with finished contact when actuated against it.

The manner of using my invention is as follows:

A screw is first cut of the size desired, or a straight tap is selected of the desired size, either of which is placed in the dies, which are then closed upon it. The gauge-collar *a* is then moved down in contact with the end *b*, and the indices *e d* brought to coincide. The set-screw *g* is then tightened to hold the collar firmly.

The work is then put in, and the screw-plate used in the usual manner.

The shoulder *f*, forming part of the handle *D*, is graduated with marks perpendicular to the plane of the face of the shoulder, which are arranged to bear a certain known relation to the pitch of the screw, whereby one complete revolution of the screw will close the dies a certain predetermined distance, and from this device a means of ascertaining the size of the screw being cut is obtained, for by looking across from the index-mark on the collar to the graduations on the shoulder, the mark is noted, and fraction of a complete turn of the handle is known.

The collar may be placed on a closing-screw when the same is separate and distinct from the handle, as is frequently the case in screw-plates.

I claim as new, and desire to secure by Letters Patent—

In combination with a screw-die plate and the screw-handle *C*, the indexed collar *a*, and the indexed shoulders *b* and *f*, arranged substantially as described.

The above specification of my invention signed by me, this day of , 1868.

JOHN S. DUTTON.
